CLAIM

The ornamental design for a brush for vacuum cleaner, as shown and described.

DESCRIPTION

1. Brush for vacuum cleaner

1.1 is a perspective view of a brush for vacuum cleaner showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof;

1.8 is a perspective view thereof in an extended position; and

1.9 is a perspective view thereof showing a flexible arm in the extended position.
